ELEVATOR CAR CONTROL

Harry R. Cullmer, Hollis, N. Y.

Application November 13, 1935, Serial No. 49,507

20 Claims. (Cl. 187—31)

My invention relates to improvements in elevator hatch-way door locks and mechanism for the control and operation of elevator cabs or cars, and is for the most part a continuation of my former application, S. N. 396,964 (now Patent Number 1,945,734), and my copending patent applications serially numbered 557,016 and 743,888.

Referring to the accompanying drawings, Fig. 1 illustrates a vertical longitudinal view of a suitable form of lock embodying an application of my invention with the cover removed. Fig. 2 is a view looking from left to right thereat, parts being broken away and parts in section. Fig. 3 is a cross section on the line 3—3 of Fig. 1. Fig. 4 is a similar view to Fig. 1, illustrating modifications. Fig. 5 is a perspective view of part of the switches shown in Figs. 4 and 7, and Fig. 6 is a similar view of another part thereof. Fig. 7 is a view looking from left to right on Fig. 4. Fig. 8 is a detail in perspective showing part of the door, frame and lock, parts being broken away and parts in section, and Fig. 9 shows the same in horizontal cross section. Fig. 10 is a view in front elevation, parts being in section and parts broken away, illustrating modifications in the door, frame and lock mechanism, and Fig. 11 is an enlarged detail of one of the locking bolts.

Fig. 13 indicates the box or casing of the lock which may be partitioned with insulating material such as fibre or bakelite 14, 15, the same being adapted to support parts of the electrical switches as hereinafter described, and being 35 slidably removable from the grooves 16. Preferably within the lower part of the box is rotatably mounted the shaft 17, to which is secured the L-shaped member comprising the bolt 18 and arm 19, the former to engage and lock 40 the door beyond the case of the lock, and the latter to pivotally carry the short circuiting bridge 20, shown to advantage in Fig. 5, for closing the main line circuit at the terminals 21, 22, and a bifurcated lug 23 is also preferably formed at the heel of the L-shaped member 45 to engage the pin 24 upon the shaft 25, carrying the operating lever 26, which is provided with a roller 27, which is in the path of the retiring cam on the elevator car.

Fig. 28 indicates a substantially flat Z-shaped insulating member or separator between the terminals 21, 22, and is suitably secured to the partition 15 with which it is removable with said terminals secured thereto by the binding posts 55 21', 22'. The top of the arm 19 terminates in

a flat table-like support 35, which carries a plate of insulation such as mica 29, and upon this plate of mica are secured blocks of fibre 30, 31, having opposed rectangular channels to receive the square tube 32, within which is slidably mounted the square plunger 33, the compression spring 34 normally projecting the plunger 33 leftwardly through the tube 32, looking at Fig. 1, the screws 42 passing through the insulating members clear of the tube 32 into the 10 table support 35, and 36 indicates another compression spring mounted over the stud 37, projecting from the base 38 at one end of the spring, the other end of said spring being over the stud 39 extending from beneath the table 15 35. 40 indicates a boss which may be cast upon the outside of the box around the hole 41 to prevent the insertion of a narrow strip or wire between the end of the door and lock to lift the bolt 18.

Referring now to the upper part of the box, shown in plan view in Fig. 3, it will be observed that a pair of contact bearings 43, 44 are secured to and removable with the partition 14, the binding posts 45, 46 being in the push button circuit. Upon the bearings are pivotally mounted the movable contacts 47, 48, the same being normally projected as shown in Fig. 3 by the compression springs 49, 50, in the path of movement of the door contacts 51, 52, which 30 comprise round headed pins with reduced shanks which pass through the insulation tubes 51', 52', into the metal bridge or plate 53, having insulated plates 54, 55, thereby insulating the door contacts from the housing 56, said housing having a leg 57 extending at right angles thereto, and being secured to the end of the door preferably as shown, holes 58, 59 being provided through the door frame which register with holes 60, 61 through the box or casing 13 to allow for 40 the passage of the door contacts 51, 52 to the movable contacts 47, 48 within the lock, the door framing 64 being widened or extended as shown at 62 to allow for the projection of the housing 56 beyond the end of the door and over 45 the face of the framing on the hall and corridor side of the hatch-way, and in order to bring the lock in position for the door contacts, the same is preferably secured within the door frame as shown preferably by supporting brackets such 50 as 63.

Referring now to Figs. 4 to 7 inclusive, the L-shaped member comprising bolt 18, arm 19 and fork 23 shown in Figs. 1 and 2 is interchangeable with a similar member shown in Figs. 4 and 7, 55

where the bolt 18 is shown with a hook end 65 in dotted outline thereby adapting the swing door lock there shown as applicable for a sliding door. In the upper part of the lock shown in Figs. 4 5 and 7, the door contacts and associated parts shown in Figs. 1, 2, and 3 are omitted, and a pivoted member 66 is provided so that no contacts are required on the door, and the push button circuit is controlled and operated by parts 10 entirely within the lock. For this purpose the member 66 is pivotally mounted at 67, and is provided with side bevels 68, 69 to accommodate either right or left swinging doors, and is provided with a nose 70 to accommodate a sliding 15 door. Whatever door is used, it swings the member 66 into the lock when the door closes, and the member 66 returns to the position shown as the door is opened. Upon the heel of the member 66 are spring projected slidable plungers 20 33 and bridge member 20 as previously described in connection with Figs. 1 and 2. Upon the insulation partition 71 are secured terminals 72, 73 of the push-button circuit, separated by the L-shaped insulating piece 74 also secured to the 25 partition 71, the movable bridge 20 closing the push button circuit when the door is closed. 75 indicates an opening through the wall of the box for the lead wires, and 76 an opening for the nose of the contact member 66.

30 Referring now to Figs. 10 and 11, it will be observed that the lock in the door frame is the same as shown in Figs. 4 and 7, except that the member 66 is not provided with the double beveled nose, and when the door is opened the nose of 35 member 66 fills the opening 76 flush with the outside of the lock case. The member 77, pivotally mounted at 78 in the door frame is provided with the double beveled nosing to accommodate right or left swinging doors and sliding 40 doors, and the nosing is somewhat longer so as to operate in advance of the actual closing of the door, so that the handle of the door can be operated when the door is closed and the car is at the floor. The rod 78 is pivotally mounted 45 upon the member 77 as shown, and may pass through the bracket 79 beneath which may be provided with the compression spring 80, resting upon the extension bolt 81, pivotally connected to the rod 78, the lower end of the extension 50 bolt 81 being preferably beveled, and passes through the lock case 13 and insulation partition 71 as shown. The bolt 81 resting behind the lug 82 of the member 66, prevents closing the push button circuit while the door is open, but when 55 the door is closed, it strikes the member 77 raising the rods 78, 81, and clears the lug 82 on member 66 which is now in the path of the bolt 83 of the door lock 93. This bolt is slidably mounted in the bearings 84, 85, and is cut away at 60 86 to house the ball end 87 of the lever 88, mounted upon the handle spindle of the door, the lower end of the lever 88 being similarly housed in the bolt 89, slidably mounted in bearings 90, 91, and the bolt 83 is also preferably spring projected as 65 shown at 92, so that when the door is closed and the handle is turned clockwise looking at Fig. 10, the push button circuit is closed due to the withdrawal of the rod 81 and the projection of the bolt 83, while at the same time the bolt 89 is withdrawn and allows the bolt 18 to drop down and 70 lock the door beyond the door frame. Also the end engagement of the bolts 89 and 18 when the door is closed, prevents the turning of the door knob while the car is away from the landing. 75 The face plate 93' of the door lock 93 is also

preferably depressed as indicated at 94, to clear the enlargement or boss 40 of the frame lock 13. When a swing door is used the ends of the bolts 18 and 89 are preferably oppositely beveled as shown, but when a slide door is used and the hook form of bolt is required, then the end of the bolt 89 is preferably flat or straightened.

Of course it will be understood that various modifications may be made in the construction and arrangement of parts without departing from the spirit of the invention as claimed.

I claim:

1. In an elevator hatch-way door and frame combination having a hinged elevator hatch-way door and a frame therefor, a lock operatively associated therewith having door engaging means, said lock extending rearwardly of the face of and within said frame and substantially clear of the door opening, electrical switches in the upper and lower portions of said lock, means in combination with one of said switches for operating said door engaging means, means externally of said lock and in the path of movement of an elevator car for actuating said first mentioned means, said door-frame having an opening therethrough leading to said lock, said last mentioned means extending beyond said door and adapted to pass through said opening into said lock, means in combination with said door and permanently projecting therefrom for operating the other of said switches simultaneously with the operation of said door.

2. In an elevator hatch-way door and frame combination having a hinged elevator hatch-way door and a frame therefor, a lock operatively associated therewith, said lock extending rearwardly of the face of and within said frame and clear of the door opening thereof, electrical switches in said lock, means in combination with one of said switches for locking said door, means externally of said lock in the path of movement of an elevator car for actuating said first mentioned means, said door-frame having an opening therethrough leading to said lock, said last mentioned means extending beyond said door and adapted to pass through said opening into said lock, means in combination with said door and permanently projecting therefrom for operating the other of said switches simultaneously with the operation of said door.

3. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, said door-frame having an opening therethrough leading to said lock, said last mentioned means extending beyond said door and adapted to pass through said opening into said lock, means in combination with said door permanently projecting therefrom for operating the other of said switches simultaneously with the operation of said door, said first mentioned means being entirely within said lock when said door is opened.

4. In an elevator hatch-way door and frame combination having an elevator hatch-way door and a frame therefor, a lock operatively associated therewith, said lock extending rearwardly of the face of and within said frame and sub-

- stantially clear of the door opening thereof, electrical switches in said lock, means in combination with one of said switches for locking said door, means externally of said lock in the path of movement of an elevator car for actuating said first mentioned means, and means in combination with said door for operating the other of said switches simultaneously with the operation of said door, said last mentioned means comprising 5
- 10 an angle plate having one leg thereof parallel with the face and extending beyond the end of said door, and having short circuiting means projecting therefrom adapted to pass through said frame and the casing of said lock.
- 15 5. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said 15
- 20 first mentioned means, said door-frame having an opening therethrough leading to said lock, said last mentioned means extending beyond said door and adapted to pass through said opening into said lock, means in combination with said door for operating the other of said switches simultaneously with the operation of said door, said last mentioned means comprising a short circuiting member adapted to be moved into said lock simultaneously with the movement of said 25
- 30 door.
- 35 6. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating 35
- 40 said first mentioned means, means in combination with said door for operating the other of said switches simultaneously with the operation of said door, and means externally of said lock and in combination with said door for locking both of said switches, and for additionally locking said door, and for locking said first mentioned door locking means.
- 45 7. In an elevator hatch-way door and frame combination having an elevator hatch-way door and a frame therefor, a lock operatively associated therewith, said lock extending rearwardly of the face of and within said frame and substantially clear of the door opening thereof, electrical 45
- 50 switches in said lock, means in combination with one of said switches for locking said door, means externally of said lock in the path of movement of an elevator car for actuating said first mentioned means, means in combination with said door for operating the other of said switches simultaneously with the operation of said door, said switches having interchangeable parts.
- 55 8. In an elevator hatch-way door and frame combination having an elevator hatch-way door and a frame therefor, a lock operatively associated therewith, said lock extending rearwardly of the face of and within said frame and substantially clear of the door opening thereof, electrical 55
- 60 switches in said lock, means in combination with one of said switches for locking said door, means externally of said lock in the path of movement of an elevator car for actuating said first mentioned means, means in combination with said door for operating the other of said switches simultaneously with the operation of said door, and transverse insulation partitions removably mounted in said lock with parts of said switches.
- 65 9. In an elevator hatch-way door and frame combination having an elevator hatch-way door and a frame therefor, a lock operatively associated therewith, said lock extending rearwardly of the face of and within said frame and substantially clear of the door opening thereof, electrical 65
- 70 switches in said lock, means in combination with one of said switches for locking said door, means externally of said lock in the path of movement of an elevator car for actuating said first mentioned means, and means in combination with said door for operating the other of said switches simultaneously with the operation of said door, said door locking means 70
- 75
10. In an elevator hatch-way door and frame combination having an elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, means in combination with said door for operating the other of said switches simultaneously with the operation of said door, and means externally of said lock and in combination with said door for locking one of said switches.
- 15 11. In an elevator hatch-way door and frame combination having an elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, means in combination with said door for operating the other of said switches simultaneously with the operation of said door, and means externally of said lock and in combination with said door for locking both of said switches, and for additionally locking said door, and for locking said first mentioned door locking means.
- 20 12. In an elevator hatch-way door and frame combination having an elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, and means in combination with said door for operating the other of said switches simultaneously with the operation of said door, said door locking means 75

adapted for interchangeable swing and slide door engaging means.

13. In an elevator hatch-way door and frame combination having an elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, means in combination with said door for operating the other of said switches simultaneously with the operation of said door, and means externally of said lock and in combination with said door for locking one of said switches, and for releasing said switch in advance of the complete closing of said door.
14. In an elevator door locking mechanism, means within the door frame and in combination with the handle of the door for closing an electric circuit and clearing the bolt of said lock to engage said door when said handle is turned in one direction, and for breaking said circuit and preventing said bolt from engaging said door when turned in the reverse direction, and means for obstructing access to the interior of said locking mechanism within said door frame when said door is open.

15. In an elevator door locking mechanism, means within the door frame and in combination with the handle of the door for closing an electric circuit and clearing the bolt of said lock to engage said door when said handle is turned in one direction, and for breaking said circuit and preventing said bolt from engaging said door when turned in the reverse direction, and means for obstructing access to the interior of said locking mechanism within said door frame when said door is open.

16. In an elevator door locking mechanism, means within the door frame and in combination with the handle of the door for closing an electric circuit and clearing the bolt of said lock to engage said door when said handle is turned in one direction, and for breaking said circuit and preventing said bolt from engaging said door when turned in the reverse direction, said lock having bolt receiving means adapted for receiving interchangeably, bolts for cooperating with pivoted and sliding doors.

17. In an elevator hatch-way door and frame combination having an elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of the elevator car for actuating said first mentioned means, means in combination with said door for operating the other of said switches simultaneously with the operation of said door, said last mentioned means comprising an angle plate having one leg thereof paral-

lel with the face and extending beyond the end of said door, and having short circuiting means projecting therefrom adapted to pass through the casing of said lock, said frame extended in alignment with the plane of the face of said door and parallel with said lock.

18. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, said door-frame having an opening therethrough leading to said lock, said last mentioned means extending beyond said door and adapted to pass through said opening into said opening into said lock, means in combination with said door and permanently projecting therefrom for operating the other of said switches simultaneously with the operation of said door, the front and back of said lock substantially in alignment with the front and back of said door.

19. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, said door-frame having an opening therethrough leading to said lock, said last mentioned means extending beyond said door and adapted to pass through said opening into said lock, means in combination with said door permanently projecting therefrom for operating the other of said switches simultaneously with the operation of said door, and said door locking means entirely within said lock when said door is opened.

20. In an elevator hatch-way door and frame combination having a hinged elevator hatch-way door and a frame therefor, a lock operatively associated therewith, said lock extending rearwardly of the face of and within said frame and substantially clear of the door opening thereof, electrical switches in said lock, means in combination with one of said switches for locking said door, means externally of said lock in the path of movement of an elevator car for actuating said first mentioned means, said door-frame having an opening therethrough leading to said lock, said last mentioned means extending beyond said door and adapted to pass through said opening into said lock, means in combination with said door and permanently projecting therefrom for operating the other of said switches simultaneously with the operation of said door, and said lock being also substantially clear of the elevator shaft.
